UNITED STATES PATENT OFFICE.

JOSEPH P. RICHARDSON, OF OAKLAND, CALIFORNIA.

WIRE-CRIMPING MACHINE.

Application filed February 9, 1925. Serial No. 7,912.

My invention relates to improvements in machines for crimping wire screen to form metal furring of the character used in applying plaster, stucco, and the like upon the 5 walls of buildings, and particularly to a machine for crimping wire screen of the character commonly known as "chicken wire" to form indentations in the strands thereof whereby the body of the screen may be held 10 in spaced relation to a wall.

The primary object of my invention is to provide an improved machine for crimping wire screen to form self spacing metal furring.

15 Another object is to provide a machine which will crimp screen to form separate indentations in the strands by stretching the wire adjacent the indentations and without reducing the effective length and area of the 20 screen.

A further object is to provide a machine of the character described which will provide indentations in longitudinally and transversely spaced relation.

25 Another object is to provide an improved machine of the character described having means for feeding wire screen between a pair of crimping rollers and adapted to align desired strands of said screen with the 30 crimping means to form indentations at desired points along the screen.

35 A further object is to provide an improved crimping machine adapted to crimp strands of wire screen fed therebetween from a roll of screen carried by a dispensing reel and provided with improved means for rewinding the crimped screen to maintain a tension upon the screen and prevent shortening of the screen during the crimping 40 thereof.

Another object is to provide a device of the character described provided with crimping rollers resiliently held in proximate relation to prevent shearing of the screen.

45 A still further object is to provide an improved machine which will be simple and positive in its operation and which will permit the efficient crimping of screen at a nominal cost.

50 I accomplish these and other objects by means of the device disclosed in the drawings forming a part of the present specification wherein like characters of reference are used to designate similar parts throughout said specification and drawings and in which,

Fig. 1 is a front elevation of my improved crimping machine.

Fig. 2 is a longitudinal vertical section taken upon the line 2—2 of Fig. 1 in the 60 direction indicated.

Fig. 3 is a side elevation of the machine showing the driving mechanism thereof.

Figs. 4 and 5 are enlarged sectional details showing the action of the crimping die portions.

Fig. 6 is a transverse sectional view through the rewinding means showing the structure thereof.

Fig. 7 is a transverse section through the 70 crimping roll bearings.

Referring to the drawings the numeral 1 is used to designate in general the body frame of the machine, said frame being supported upon suitable legs 2. A pair of 75 crimping rollers 3 and 4 are mounted upon the body 1 adjacent one end thereof and a pair of feed rollers 5 and 6 are mounted upon the body adjacent the opposite end thereof.

The crimping rollers are arranged in horizontal parallel relation with one roller directly above the other roller. One of the rollers, preferably the lower roller 4 is mounted within fixed bearings 7 secured upon the sides of the frame 1 at the ends of said roller. The other roller 3 is mounted within bearings 8 slidably mounted within brackets 9 above the fixed bearings 7. Plates 11 mounted above the bearings 8 are engaged by springs 12 mounted upon bolts 13 extending through apertures in said plates and threaded into the upper ends of the brackets, said springs being placed under sufficient compression to normally depress the bearing 95 and resiliently hold the upper bearing in proximate relation to the lower roller for a purpose hereinafter more fully explained.

The lower crimping roller 4 is provided with a plurality of radially disposed outwardly extending male die portions 14 formed upon the surface of the roller and arranged to be engaged by a like plurality of oppositely disposed female die portions 16. The die portions 14 and 16 are spaced circumferentially around the roller so that for each rotation of the rollers successive die portions will be moved into operative engagement to form crimps in spaced relation along a length of screen fed therebetween as hereinafter more fully explained. The die portions are preferably made in rela-

tively short lengths spaced longitudinally along the roller to allow a space in which the screen is not indented between adjacent die portions so that the indentations formed by said die portions may be spaced transversely across the width of the screen. The die portions are also preferably offset circumferentially with respect to the die portions adjacent the ends thereof so that the indentations formed by each set of dies will be spaced longitudinally as well as transversely to adjacent indentations upon the screen. This arrangement of the die portions is provided for the purpose of making furring of the character disclosed in the pending application of Carl Gilmore, Serial Number 7,927, filed February 9th, 1925, wherein the advantages of this particular arrangement is specifically explained. This specific arrangement of the die portions may of course be modified in numerous ways to indent wire in any of a great number of ways for different specific purposes and I therefore do not wish to restrict myself to the precise arrangement of die elements herein disclosed.

The feed rollers 5 and 6 are mounted in proximate relation to engage and feed a length of wire screen from a roll 17 rotatably mounted between brackets 18 secured upon the rearward end of the machine. The feeding rollers are arranged to engage the screen with sufficient pressure to feed the screen forwardly to the crimping rollers 35 and at the same time straighten out the screen so that the screen will lie flat when extended. The upper feed roller 5 is provided with a plurality of pins 19 arranged to pass through interstices of the screen and to be received within corresponding recesses 21 formed in the lower roll whereby the screen will be fed in uniform relation to the die portions of the crimping rollers and cause a desired portion of the strands of said screen to be engaged and indented as hereinafter more fully explained. The feed rollers also engage the screen with sufficient pressure to prevent any longitudinal sliding movement of the screen when the strands 40 are indented between the die portions of the crimping rollers thereby causing said strands to be stretched to form the loops without causing any shortening of the screen and without reducing the total effective area of the screen.

A guide 22 is mounted between the feeding rollers and the crimping rollers, said guide consisting of upper and lower plates adapted to hold the screen in flat position between said rollers and connected along the side to hold the screen in alignment with the crimping rollers.

After the screen has been crimped between the crimping rollers 3 and 4 it is carried over an arcuate guide surface 23 to

be rewound upon a rewinding roll 24 mounted between brackets 26 secured upon the adjacent end of the machine. The roll 24 is apertured at its ends to receive supporting elements 27 removably connected thereto and arranged to be received within bearings 28 and 29 formed upon the brackets 26. One of said elements 27 is provided with a squared shank 31 adapted to be inserted through a corresponding shaped aperture in a bushing 32 rotatably mounted within the bearing 29. A friction plate 33 is secured in connection with the outer end of the bushing 32. A gear 34 is rotatably mounted adjacent the plate 33 upon an extension 35 of the bushing 32 said gear 34 being provided with a friction surface arranged to be held in frictional engagement with the plate 33 by means of a plate 36 held against the opposite side of the gear by means of springs 37 mounted upon bolts 38 threaded through the outer plate 36, and into the extension 35 of the bushing 32 whereby a frictional driving contact will be maintained between the sides of the gear and the plates. The gear 34 is arranged to be driven by a pinion 39 mounted upon a shaft 41 and driven by a sprocket chain 42 engaging a sprocket 43 associated with said pinion 39. The shaft 41 is mounted upon a bar 44 pivotally mounted upon the machine as at 46, said bar being pivotally movable to permit the pinion 39 to be lifted out of engagement with the gear 34 to facilitate the placing and removal of the roll 24 and the attachment of the screen upon said roll.

The feeding and crimping rollers are rotated simultaneously in the same direction and at the same peripheral speed by means of a motor 47 connected to said rollers through a suitable train of gears consisting of a driving pinion 48 mounted upon a main drive shaft 49 driven by the motor through a chain 51 mounted over sprockets 52 and 53. The pinion 48 meshes with a large gear 54 mounted upon a shaft 56 upon which is mounted a pinion 57. Large gears 58 mounted upon outwardly extending ends of shafts 59 and 61 mesh with the pinion 57 upon opposite sides thereof, said shafts 59 and 61 carrying the lower crimping roller and feed roller respectively. Gears 62 and 63 mounted upon the shafts 59 and 61 respectively engage corresponding gears 64 and 66 carried by the shafts 67 and 68 of the upper crimping rollers and feed roller respectively whereby said upper rollers will be positively driven by the corresponding lower rollers. The gears are designed to obtain a desired speed reduction between the motor 47 and the feed and crimping rollers.

In operation, a roll of screen to be crimped is mounted upon a rod 69 mounted between the brackets 18. The screen used is prefer-

ably of the character commonly known as "chicken wire" wherein strands of wire are interwoven and twisted together to form substantially hexagonal interstices of relatively 5 large size. The screen is threaded from the roll 17 between the feed rollers 5 and 6, through the guide 22 and thence between the crimping rollers 3 and 4. The end of the screen is carried downwardly and connected 10 to the roll 24. When now the machine is set in motion the screen will be unrolled from the roll 17 by the feed rollers and fed between the crimping rollers. As the screen is moved between the crimping rollers 3 and 15 4 the male die portions 14 press the wire strands engaged thereby into the female die portions 16 to crimp said strands into loops 71 said loops being formed by stretching the strands of wire to form indentations without 20 reducing the length of the screen and without reducing the total effective area of said screen. This result is accomplished by holding the screen between the feed rollers in such manner that sliding movement of the 25 screen is prevented.

As the screen is moved from between the crimping rollers it is rewound upon the roll 24 which is frictionally driven by the gear 34. The gear 34 is driven by the chain 42 which in turn is driven by means of a pinion 72 mounted upon a bracket 73 and meshing with one of the gears 58, said pinion being mounted in connection with a sprocket arranged to receive said chain 42. The friction 30 between the sides of the gear 34 and the plates 33 and 36 is sufficient to rotate the bushing 32 and the roll 24, and at the same time to permit sufficient slippage to keep the screen drawn tight between the crimping rollers and the roll 24 without straightening 35 out the indentations formed in the screen, and also to insure the proper winding of the screen as the diameter of the roll increases. The continuous rotation of the screen causes 40 indentations to be made at regular intervals throughout the length and width of the screen.

The die portions 14 and 16 are preferably so arranged that the indentations will be 45 formed upon the twisted strands forming opposite sides of interstices, said strands being indented to form separate and independent loops extending upwardly from the screen. As the screen is rewound into a roll, the 50 loops, being formed independently from the strands of wire along the sides of interstices, are received within the interstices of successive layers of screen so that the crimped screen may be rolled into a roll of the same 55 size as the original flat screen before crimping. The rollers and the rewinding means is so arranged that the lugs will be outwardly disposed with respect to the rolled screen whereby the screen may be unrolled 60 along a wall and the lugs caused to engage

said wall and hold the main body of the screen in spaced relation to the wall.

The resilient mounting of the upper crimping roller 3 is particularly provided to avoid the possibility of shearing the screen between the die portions 14 and 16. When opposite die portions move into engaging relation as shown in Figs. 4 and 5 of the drawings, the strands of wire are pressed by the male die member 16 into the opposite die portion 16 70 to shape the loops. The springs 15 permit the upper crimping roller to be lifted slightly against the pressure of said springs whereby the wire may be pressed firmly into shape without danger of shearing through the screen. The springs also provide a resilient pressure adapted to compensate for any difference in the thickness or number of the wire strands engaged between the rollers 3 and 4. 75

From the above explanation it will be 80 seen that I have provided a new and improved machine of the character described. While I have illustrated and described only what I now consider to be the preferred form of my invention, the specific form and 85 arrangement and the details of construction may of course be modified in numerous ways without departing from the spirit of my invention. I therefore do not wish to restrict myself to the precise structure disclosed but 90 wish to avail myself of such modifications as may fall within the scope of the appended 95 claims.

Having thus described my invention what I claim as new and desire to secure by Letters Patent is:

1. A wire crimping machine comprising a pair of crimping rollers resiliently mounted in proximate relation, said rollers being provided with oppositely disposed male and female die portions to form loops in wire screen by stretching strands thereof adjacent said die portions; feed rollers adapted to feed the screen to the crimping rollers; and means for rotating the crimping rollers and the feed rollers in timed relation; and means mounted upon the feed rollers and engaging interstices of the screen for aligning desired portions of the strands with the die portions of the crimping rollers; and means for rotating the crimping rollers and the feed rollers in timed relation. 105

2. A wire crimping machine comprising a pair of crimping rollers resiliently mounted in proximate relation, said rollers being provided with oppositely disposed male and female die portions adapted to form loops in wire screen by stretching strands thereof adjacent said die portions; feed rollers adapted to feed the screen to the crimping rollers; and a guide mounted between the feed rollers and the crimping rollers for holding the screen flat and in alignment with the rollers. 110

3. A wire crimping machine comprising a 115

- pair of crimping rollers mounted in proximate relation, said rollers being provided with oppositely disposed male and female die portions adapted to form loops in wire screen by indenting strands thereof at spaced points along a roll of screen fed therebetween; and means for rotating the rollers; and feed rollers mounted in spaced relation to the crimping rollers for feeding the screen and for holding said screen while said screen is engaged between die portions of the crimping rollers whereby the strands may be stretched to form indentations without shortening the screen or reducing the surface area thereof.
4. A wire crimping machine comprising a pair of crimping rollers mounted in proximate relation, said rollers being provided with oppositely disposed male and female die portions adapted to form loops in wire screen by indenting strands thereof at spaced points along a roll of screen fed therebetween; and means for rotating the rollers; and feed rollers mounted in spaced relation to the crimping rollers and rotated simultaneously therewith for feeding screen therebetween; and means mounted upon the feed rollers for aligning desired portions of the strands with the crimping dies.
5. A wire crimping machine comprising a pair of crimping rollers mounted in proximate relation, said rollers being provided with oppositely disposed male and female

die portions adapted to form loops in wire screen by indenting strands thereof at spaced points along a roll of screen fed therebetween; and means for rotating the rollers; feed rollers rotated simultaneously with the crimping rollers for feeding screen therebetween; a reel mounted upon one end of the machine and adapted to support a roll of screen to be dispensed between the rollers; and rewinding means mounted upon the opposite end of the machine for winding the crimped screen into a roll. 45

6. A wire crimping machine comprising a pair of crimping rollers mounted in proximate relation, said rollers being provided with oppositely disposed male and female die portions adapted to form loops in wire screen by indenting strands thereof at spaced points along a roll of screen fed therebetween; a pair of feed rollers adapted to feed screen between the crimping rollers; means for rotating the crimping rollers and the feed rollers; means mounted upon one end of the machine for supporting a roll of screen to be dispensed to the feed rollers; and frictionally driven rewinding means mounted upon the opposite end of the machine for rewinding the crimped screen into a roll. 55 60

In witness whereof I hereunto set my signature.

JOSEPH P. RICHARDSON.
